TRAVEL GAME BOARD AND PEGS

Harry J. Ferling, Baltimore, Md.

Application July 9, 1951, Serial No. 235,786

1. Claim. (Cl. 273—130)

1

This invention relates to educational and amusement devices and more particularly to games requiring alertness, physical manipulation and mental calculation wherein the use of pegs is involved, along with pictures of recognizable identity and the placement of one adjacent the other, when an extraneous event occurs in which there is a suitable connection, to be recorded or noted.

There are various types of games which require the use of pegs or other items by the players when something occurs that requires their movement to a particular location on an illustrated board employed in connection with playing the game. They each have a particular use and interest to the particular type of players that are called into the game. In this invention, the players are served with pegs set in reserve holes in a board and made removable, to be placed in other holes in certain representations of articles of common acquaintance, when they are seen on the landscape where the players are travelling. Thus in travelling in a vehicle, such as an automobile, train, ship or airplane, the passing of a subject located in the vicinity passed and also pictorially represented on the board calls for the movement of a peg from the reserve hole in which it is normally stored, to the hole provided in the representation. The players by acting promptly and correctly build up a score by their efforts depending on their individual alertness and accuracy, until one of them wins the game. The rules of the game are made to suit its purpose and facilities.

The invention has for its object the provision of a playing board and pegs that can be used by players, particularly during travelling in a vehicle, to improve their observational powers, competitive instincts and coordination between their eyes and hand.

Another object of the invention is to provide a new and improved playing board, portable enough to be carried and used while travelling in a vehicle, and requiring continual alertness and observation of environment, with the operation of pegs or the like to play the game effectively.

Other objects will become apparent as the invention is more fully outlined.

For an understanding of the invention and the manner of playing the game involved, reference is made to the accompanying drawings, which show a particular form of the game by way of example. The following explanation in cooperation with the drawings makes the mode of play-

2

ing the game apparent, while the claim emphasizes its general scope.

In the drawings:

Figure 1 is a view in perspective of a playing board embodying this invention;

Figure 2 is a partial section of the board, taken on the line 2—2 of Figure 1; to show other playing boards nested therein;

Figure 3 is a detail of the type of peg used with this embodiment;

Figure 4 is a detail of the mechanical indicator operated when the game is stopped by the insertion of a peg in a selected hole; the view being shown in plan in conjunction with a portion of the board;

Figure 5 is a side elevation of the indicator, with dotted outline to show its position when operated by a peg; and

Figure 6 is an enlarged detail of a portion of the board with a printed item and grommeted hole.

Similar parts throughout the drawings are represented by the same reference numerals.

The board used in this embodiment is preferably in the form of a cardboard box 10, on the enclosing cover 11 of which is printed a typical scene or landscape 30. On the landscape, a barn 12 is shown, a cow 13, a tree 14, a pond 15, a series of bushes 16, an airplane 17, a rabbit 18, and a gate 19 leading to one of the enclosures forming a farm and a "Stop" sign 25. In addition there is a white horse 20 arbitrarily used for the termination of the game. Each of the above items from 12 to 20 inclusive has adjacent grommeted openings 21 and 26 in which the restricted sized shank 32 of a peg 22 can be inserted by the player at the proper time. Normally the pegs 22 are kept inserted in storage holes 21 arranged in a corner section 24 of the board, ready for removal and replacement in the individual peg holes 21 as the rules of the game indicate that it be located.

The grommeted opening 26 in the white horse outline is so located that the insertion of the shank of the peg 22 through it causes a cardboard indicator 27 to be tilted. When the indicator 27 is tilted it rises from the face of the board 10 and shows the player that the White Horse has been played. This finishes the game or may be used as a penalty. The indicator consists of a lever 28 fulcrumed on a piece 29 and aligned so the shank 32 will push against it when inserted through the peg hole 26 and make it rise conspicuously above the board level. Other boards 40 and 50, and pegs are nested in the box 10 to be used by other players.

The game can be played during travelling by distributing a series of the boards among the players. The players then hold the boards on their knees and watch the terrain as they travel. If they see a cow in a field, the player having a cow on his board immediately places a peg 32 in the hole 21 in the cow 13. If a gate is seen, then the peg is placed in the hole 21 of the gate 19, and so on. If a white horse should appear in the neighborhood, the shank of a peg is inserted in the hole 26 of the horse 20 and the indicator is raised to show the game is over, or it may be a penalty and all players clear their boards and start over again.

The game may be played in other ways and the scenery of the board may be varied to suit. If the players are not travelling and wish to play the game, they refer to some suitable book and turn the pages until the various items show illustrated on its various pages. When they so appear the pegs are used in the same way as that previously described. If pictorial cards are used the system followed is the same. In this way the game is not restricted unduly. Since the boards do not have the same items represented on them, one board could be filled with pegs before another, and the one first filled will be the winner.

It will be noted that the players are kept alert since the particular items on the scene may appear at any moment, and when they do so, the players can insert the pegs in the manner described or lose out if they don't. Coordination in the handling of the pegs is also required, and judgment and accuracy are needed to place the pegs in the right holes at the moment. In this way interest is induced in the players and has considerable educational value. The board is made in the form of box for commercial reasons. This form is attractive and at the same time can be used for holding the pegs and instructions used in the game. The box raises up the cover to a height sufficient to permit the pegs to be inserted without obstruction.

In Figure 6, the outline 41 is made arbitrarily that of a pig 41, as it belongs to one of the nested boards. The grommet 42 is inserted in the peg 45 hole to strengthen it and increase the life of the board, as well as provide a conspicuous cell in which to insert the peg used in it. All the boards preferably have a White Horse operable in the manner already described, so that the player who

sees it first and operates the indicator will win or start all over again.

While but one general form of the invention is shown in the drawings and described in the specification, it is not desired to limit this application for patent to this particular form as it is appreciated that other forms of construction could be made that would use the same principles and come within the scope of the appended claim.

Having thus described the invention, what is claimed is:

A game apparatus comprising a box, a cover therefor, said cover having printed on the upper surface thereof simulations of preselected animals and articles, the cover having a first set of holes therethrough, there being one such hole in proximity to each simulated animal and article and there also being a second set of holes through the cover, a series of pegs having an enlarged head and a smaller cylindrical extension, said heads being retained on the cover and said extensions protruding through said cover into the box, said pegs lying in the holes of the second set and being manually movable therefrom and insertible in the hole corresponding to the animal and article called to the attention of the players, and an indicator pivoted to said cover and normally lying beneath the upper surface of the cover, said indicator having a stem extending beneath one of the holes of the first set, said indicator being tilted by the insertion of a peg in the last mentioned hole to cause the aforesaid indicator to rise above the cover and remain in that position while the said last mentioned peg remains in said last mentioned hole.
